UNITED STATES PATENT OFFICE.

GILBERT WRIGHT AND CHRISTIAN AALBORG, OF WILKINSBURG, PENNSYLVANIA, ASSIGNORS TO THE WESTINGHOUSE ELECTRIC AND MANUFACTURING COMPANY, OF PENNSYLVANIA.

SWITCH FOR ELECTRIC CIRCUITS.

SPECIFICATION forming part of Letters Patent No. 633,771, dated September 26, 1899.

Application filed January 30, 1899. Serial No. 703,783. (No model.)

To all whom it may concern:

Be it known that we, GILBERT WRIGHT, a citizen of the United States, and CHRISTIAN AALBORG, a subject of the King of Sweden 5 and Norway, residing in Wilkinsburg, in the county of Allegheny and State of Pennsylvania, have invented a new and useful Improvement in Switches for Electric Circuits, (Case No. 801,) of which the following is a specification.

Our invention relates to switches for electric circuits; and it has for its object to provide a switch of such construction that its movable contact member may be readily 15 brought into operative position, locked in such position, and released and separated from its stationary member by an expenditure of power that shall be substantially independent of the current-carrying capacity 20 of the switch and much less than that exercised in opening and closing switches of the types heretofore employed.

Manually-operated switches heretofore in use have generally been of knife-blade and 25 jaw construction, the structures being variously modified in order to increase the current-carrying capacity and facilitate the opening and closing of those of large size. The opening and closing of knife-and-jaw switches 30 having large current-carrying capacity can be effected, however, only by the application of a considerable amount of power by reason of the fact that the jaws must contain so much material that they will yield to only a very limited degree. We are enabled by our invention 35 to entirely dispense with gripping engagement between the contact-terminals of the switch, and thereby obviate deterioration by reason of frictional wear.

40 While our invention is suitable for use in connection with circuits carrying any quantity of current and any degree of electromotive force, it is especially adapted for circuits carrying heavy currents, since it insures a nearly perfect contact between the co-operating terminals, and thus permits of the employment of a less amount of copper than is necessary in other types of switches having the same current-carrying capacity.

45 In the accompanying drawings, Figure 1 is

a side elevation of one form of switch constructed in accordance with our invention, and Fig. 2 is a front elevation of the same on a smaller scale. Fig. 3 is a side elevation of a switch having a modified form of operating and locking mechanism, and Fig. 4 is a front elevation of the same on a smaller scale. Fig. 5 is a side elevation of a double-throw switch constructed in accordance with our invention, and Fig. 6 is a front elevation of the same. Fig. 7 is a detail view of the locking-head forming part of the switch mechanism shown in Figs. 5 and 6.

Referring now particularly to Fig. 1, 1 is a supporting-base, which will ordinarily be a 65 switchboard-panel of marble, slate, or other similar material.

2 and 3 are terminal studs which extend through the base-plate 1 and are respectively provided on the face of the latter with contact plates or blocks 4 and 4^a, having flat contact-surfaces parallel with the face of said base-plate.

Attached to the terminal block 4^a or to the base 1 adjacent to said terminal block are 75 two forwardly-projecting plates 5, to the outer or lower end of each of which is pivoted an arm 6, the other ends of said arms being bolted or otherwise rigidly fastened to the movable contact member 7 of the switch. This movable 80 contact member 7 is built up of thin plates bolted or riveted together at or near their middle portions and terminating at each end in a plane that is substantially parallel to the faces of the terminal blocks or plates 4 and 4^a 85 when said member is brought nearly to its circuit-closing position. An operating arm or lever 8, provided with a suitable handle 8^a, is formed with two curved arms, the ends of which are respectively pivoted to the plates 90 5 at points materially nearer to the middle of the brush-contact member 7 than the pivotal points of the arms 6. A toggle-lever arm 9 is hinged or pivoted at one end to the lever 8 and at its other end to the arms 6, at such 95 points that when the switch is in its closed position the axis of the pivotal connection with the arms 6 will be slightly below a straight line joining the pivotal axis of the lever 8 and that between the lever-arm 9 and 100

said lever 8. The contact member 7 is provided with a lug or projection 10 and the operating-lever 8 with a similar lug 11, this being so located and of such dimensions that 5 they will come into engagement when the movable member of the switch has been moved to its locked position.

It will be seen from the foregoing description that the toggle-lever operating mechanism for the movable member of the switch is such that the switch may be very easily opened and closed irrespective of its size and carrying capacity and that when closed it will be locked and firmly held in that position by reason of the toggle-joint between the movable contact member and its operating-lever having passed slightly beyond the dead-center.

Referring now to Figs. 3 and 4, the base 2c plate or slab 1, the terminal studs 2 and 3, and their contact blocks or plates 4 and 4^a are or may be the same in construction and arrangement as the corresponding parts shown in Figs. 1 and 2. The plates 5^a, constituting, 25 the supporting-frame for the toggle-lever mechanism, perform the same function as the parts 5 shown in Figs. 1 and 2; but on account of differences in the structure and arrangement of the toggle-lever mechanism these 30 parts are shown in Figs. 3 and 4 as of different form. The supporting-arm 6^a is pivotally mounted at one end between the plates 5^a and is attached at its other end to the laminated contact member 7^a, the latter being 35 substantially the same in construction and operation as the contact member 7 shown in Figs. 1 and 2. The operating-lever 8^a, having a suitable handle 8^b, is pivotally mounted between the arms or plates 5^a and is connected 40 to the arm 6^a by means of a toggle-lever, one arm 9^a of which is pivoted to the arm 6^a at such a point that when the operating lever and handle have been moved to the position shown in Fig. 3 of the drawings—that is, to 45 such a point that the desired engagement between the laminated contact member and the stationary terminals has been effected—the toggle-joint between the two arms of the lever will be slightly above a straight line 50 joining the pivotal axis of the lever 8^a and the axis of the pivot joining the lever-arm 9^a with the arm 6^a. It will be readily seen from this construction that the movable member of the switch is easily moved toward and 55 away from the stationary terminals and that when moved to the closed position it will be securely locked.

While we have shown two combinations of devices for operating and locking a single- 60 throw brush-contact switch, we do not desire to limit our invention to these specific forms, since other modifications and variations may obviously be made by one skilled in the art without changing the substantial mode of 65 operation or result and without departing from the spirit and scope of the invention.

Referring now particularly to Figs. 5, 6,

and 7, the base-plate or switchboard-panel 1 is shown as provided with three terminal studs 12, 12^a, and 12^b, each of which has on 70 the front of the base board or panel a terminal plate or block 13, having a plane contact-surface parallel, or substantially parallel, with the face of the switchboard-panel, this number and general arrangement of stationary 75 terminals being necessary in all double-throw switches. The supporting-frame 14 for the switch-operating mechanism is supported by the middle terminal block 13 or directly by the base-plate 1, and pivotally mounted in 80 this frame is a bifurcated operating-lever 15, provided with a suitable handle 16. Mounted upon the same shafts or pivots is a bifurcated arm 17, that extends between the arms of the operating-lever 15 nearly to the point at which 85 the handle is applied. This arm 17 supports the laminated contact member 18, which is substantially the same in construction as the corresponding member shown in the preceding figures of the drawings. The supporting- 90 arm 17 has an enlarged outer end provided with a curved slot 17^a, the curvature of which corresponds to the arc of a circle having the pivotal axis of this arm and the operating-lever as a center. Pivotally mounted in the 95 outer end of the supporting-arm 17 is a locking-head 19, having two projections 20 and provided with an opening 21 of clover-leaf shape, the recesses of which are marked, respectively, 21^a, 21^b, and 21^c. The operating-lever 15 is provided with a pin 22, which extends through this clover-leaf-shaped opening 21 in the locking-head 19, and also through the slot 17^a in the supporting-arm 17. The supporting-arm 17 is connected to a lug on 100 the outer face of the locking-head 19 by means of a coiled spring 23, and a similar spring 24 connects the supporting-arm with a point on the member 18 located between its 105 pivotal support and the base 1. At each end 110 of the supporting-base 1 is a pair of standards 25, between the outer ends of which is a pin or roller 26 in such position as to be engaged by one of the projecting arms 20 of the locking-head 19. 115

The supporting-frame 14 for the operating mechanism is provided at each side with two arms 27, having inwardly-bent ends 28, so that as the contact member 18 is thrown from one side to the other these ends 28 will serve 120 as guides to prevent any tilting of the brush-contact into an inoperative position.

The operation of the invention will now be described more fully, it being assumed that the parts are in the positions indicated 125 in Figs. 5 and 6 and that it is desired to change the circuit connections from terminals 12^a and 12^b to terminals 12 and 12^a. The operator grasps the handle 16 and draws it outward, and by so doing first moves the pin 130 22 to such a point that the spring 23 will move the locking-head to throw the recess 21^b into engagement with the pin, thus releasing the supporting-arm 17 and switch-contact

member 18. As the operating-lever and handle are moved farther outward the pin 22 will move in the curved slot 17^a until it reaches its outer end, when the supporting-arm will be engaged by pin 22 and moved with the operating-lever. As the supporting-arm begins to move the spring 24 will rock the member 18 on its pivot and hold it in such position that its forward movement cannot be interfered with by the ends 28 of the upper guide-arms 27. As the movement of the lever 15 and arm 17 is continued through an arc of one hundred and eighty degrees the contact member 18 will be carried over to a position in front of the terminal blocks or plates 12 and 12^a. It will be prevented from turning into an inoperative position during this movement by the in-turned ends 28 of the lower guide-arms 27. As the contact member 18 is moved into operative engagement with the terminal-blocks the pin 22 will move into the recess 21^c of the opening 21 in the locking-head, and thus rock the head on its pivot in opposition to the pull of the spring 23, so as to bring arms 20 underneath the pin 26, and thus lock the switch in its new position.

While we have found the construction and arrangement of parts herein shown and described to be useful and effective in operation, we do not desire to limit ourselves to the specific details disclosed, since these may be modified without departing from the invention.

We claim as our invention—

- 35 1. A switch for electric circuits comprising stationary terminals having contact blocks or plates the contact-faces of which are in substantially the same plane, a supporting-base therefor, a laminated member having beveled ends for engagement with the faces of said terminals, a supporting-arm pivoted at one end to the base and attached to the laminated member at substantially the middle point of the latter and at a considerable distance from the axis of movement of said arm, and an actuating-lever pivoted to the base and having a movable connection with the supporting-arm.
- 50 2. In a switch for electric circuits, the combination with a base having stationary contact-terminals, of a laminated contact member having beveled ends adapted to engage the plane faces of said contact-terminals, a supporting-arm pivoted at one end to the base and attached to the laminated member at substantially the middle point of said member, and an actuating-lever having operative connections with the base and with the supporting-arm for the laminated member.
- 55 3. In a double-throw switch for electric circuits the combination with a base having three

contact-terminals, of an arm pivoted at one end to said base, a double-ended laminated contact member pivoted to said arm, a pivoted operating-lever and means for automatically locking the switch when the operating-lever is moved in either direction to its extreme position. 65

4. In a double-throw switch for electric circuits, the combination with a base having three contact-terminals, of an arm and an operating-lever pivoted to the base and having a lost-motion connection with each other, a double-ended laminated contact member and a locking-head pivoted to said arm, and means 70 carried by the operating-lever for moving the locking-head into locking position as said operating-lever reaches either of its extreme positions. 75

5. In a double-throw switch for electric circuits, the combination with a suitable base provided with middle and end terminals, of a laminated, double-ended contact member, a supporting-arm to which said contact member is pivoted and an operating-lever having the same pivotal axis as said arm and a lost-motion connection therewith, a locking-head pivoted to said arm, and means carried by the operating-lever for throwing said head into locking position, as the contact member 85 reaches each of its circuit-closing positions. 90

6. In a double-throw switch for electric circuits, the combination with a base having middle and end terminals, of a double-end laminated contact member, an operating-lever, a supporting-arm connecting said contact member with said base and with said operating-lever, a locking device supported by said arm and operated by said lever, as the laminated contact member reaches either circuit-closing position. 95 100

7. In a double-throw switch for electric circuits, the combination with a base having middle and end terminals, of a double-end laminated contact member, an operating-lever, a supporting-arm connecting said contact member with said base and with said lever, a locking device supported by said arm and operated by said lever, as the laminated contact member reaches either circuit-closing position, and guides for the movable contact member as it moves from the one to the other of its contact-making positions. 105 110

In testimony whereof we have hereunto subscribed our names this 25th day of January, 1899.

GILBERT WRIGHT.
CHRISTIAN AALBORG.
